UNITED STATES PATENT OFFICE.

ROBERT C. MATHES, OF NEW YORK, N. Y., ASSIGNOR TO WESTERN ELECTRIC COMPANY, INCORPORATED, OF NEW YORK, N. Y., A CORPORATION OF NEW YORK.

LOADING SYSTEM.

Application filed October 19, 1922. Serial No. 595,519.

This invention relates to loading systems and particularly to a loading system for multiplex signaling circuits.

The loading of a transmission line according to the Pupin system of loading to improve the characteristics of the line for one range of frequencies may sometimes fail to give a corresponding improvement in another range of frequencies or may even prevent transmission in that range. For example, the loading of a line or cable for telephone purposes at speech frequencies does not in general give the same uniform transmission and impedance characteristic for the frequencies employed in low frequency telegraph systems. If it were to be loaded to improve its characteristic for telegraph frequencies it probably would have an objectionable attenuation at voice frequencies.

An object of this invention is to provide means for loading a line which will be equally effective for a plurality of bands or ranges of frequency in improving the transmission and impedance characteristic of the line, such as, for example, could be employed in a line containing telegraph, telephone and carrier or ultra-audio currents.

This invention in one form comprises means for introducing independent systems of loading into the line, each of which functions for a particular range of frequencies without introducing any appreciable distortion in the transmission of currents not designed to be loaded by the loading arrangement in question. Thus, a signaling line containing both telephone and telegraph currents may be independently loaded for two types of signals by inserting the usual spaced loading coils for loading the line for telephone currents and at other points in the line inserting loading coils particularly designed to improve the transmission for telegraph frequencies. In order to prevent distortion of the telephone currents due to the presence of the inductances which load the circuit for the telegraph currents, a condenser may be shunted across the terminals of each telegraph loading inductance of such a value that the inductance and the condenser form an anti-resonant circuit for a frequency intermediate the important telegraph frequency band and the important telephone frequency band. With such an ar-

rangement the anti-resonant circuit would be substantially a capacity reactance for the telephone frequencies, while the anti-resonant circuit would present a substantially inductive reactance for the telegraph frequencies. This capacity need not be connected directly in shunt to the terminals of the loading coil but may, for example, be included in series with a winding of a transformer which is capable of repeating the telephone currents, the telegraph loading coil being connected between the primary and secondary windings of said coil.

Referring to the drawings,

Fig. 1 represents this invention embodied in a combined telephone and telegraph signaling system.

Fig. 2 is a modification of the multiplex system of Fig. 1 in which the signaling line is divided into a plurality of sections by transformers which repeat only telephone currents.

In Fig. 1, a signaling line 7 is disclosed on which, it is to be understood, are impressed both telephone frequency signals and signals of another frequency range, such as low frequency telegraph signals. A plurality of loading coils 8 are uniformly distributed along the line 7 whereby the line is loaded for telephone currents according to the Pupin system.

In order to simultaneously load line 7 for frequencies below those of importance in speech, for example, low frequency telegraph signals, this invention provides a plurality of loading coils 9 inserted at regular intervals in the line 7 but more infrequently than loading coils 8, since the distance between loading sections varies inversely with the frequency to be loaded. It has been found that no detrimental effect is produced by having the low frequency telegraph current pass through the various speech frequency loading coils since they do not possess sufficient inductance to cause appreciable distorting effects. The reverse, however, is true with respect to the passage of speech frequency currents through the telegraph loading coils 9, since coils 9 will be of sufficient inductance to seriously distort and attenuate the speech frequency signals, thereby rendering ineffective the beneficial results obtained from the insertion of the telephone loading coils 8. In order to prevent this distorting effect, the

form of this invention shown in Fig. 1 provides a condenser 10 shunted across the terminals of each of the telegraph loading coils 9. These capacities 10 preferably should have such a value that each coil 9 and associated capacity 10 form an anti-resonant circuit for a frequency intermediate the ranges of frequencies to be loaded by the various loading coils of the line. For example, these circuits should be anti-resonant for a frequency of 40 to 60 cycles in case loading coils 9 are to load the line for telegraph currents of frequencies less than 40 cycles, and loading coils 8 are to load the line for speech frequencies of 300 cycles or greater. The most desirable frequencies to choose in any particular case for this anti-resonant condition depends upon the telegraph and telephone requirements and upon the type of signaling system employed. Suppose that for an extra light loaded telephone cable with a capacity of .065 m. f. per mile we space the coils 9 fifty miles apart and give them an inductance of about 40 henrys. The telephone coils may have values of .044 henrys spaced about 6000 feet apart. Above about 100 cycles the system would function as an ordinary extra light loaded cable of 700 ohms impedance and with a cut-off frequency of 5500 cycles. In the lower frequency range it will act like a loaded line of about 3000 ohms impedance and a cut-off frequency of 30 cycles, assuming that the anti-resonant frequency is from 40 to 60 cycles.

Fig. 2 shows an alternative arrangement in which loading coils 15 are distributed along the line 16, as in Fig. 1, for loading the line 16 for speech frequency currents. At every point where it is desired to load line 16 for low frequency telegraph signals a repeating coil 18 is inserted each comprising a primary and a secondary winding. Shunted around the terminals of these windings are the telegraph frequency loading coils 20 so that for telegraph frequencies the various sections of line 16 are directly connected, while for speech frequencies they are inductively connected by the repeating coils 18. With this arrangement the speech frequency currents are not required to traverse the telegraph frequency loading coils and the telegraph frequency currents may be prevented from passing through the windings of the repeating coils 18 by including a condenser 22 in circuit with each winding of each repeating coil between the points of connection of the telegraph loading coils. These condensers as in Fig. 1 are effectively in shunt to the telegraph loading coils.

It is to be understood, of course, that the system of loading, described above, is applicable to either metallic telegraph or grounded telegraph systems, since the signaling line in both Figures 1 and 2 is shown

to be balanced, telegraph loading coils being included in each side. It is also to be understood that this invention is applicable to the loading of a plurality of frequency bands employed in signals of any desired character and the invention is not limited to the particular combination shown of a line loaded for telephone conversations and telegraph signals. For example, the system employed in Fig. 1, without modification, except as to changes in the values of the capacities and inductances and the relative distances between loading points could be employed for simultaneously loading the line for both carrier current signals of a frequency of 10,000 cycles for example, and speech frequency currents.

The blocks marked X, in shunt to each of the windings of the transformers of Fig. 2, are for the purpose of indicating at what point in the circuit it may be found preferable to introduce impedance compensators to overcome any impedance irregularities introduced in the line at the lower range of the speech frequencies due to the presence of the telegraph frequency loading coils. These compensators may be of any desired type, such as the networks described and disclosed in the Hoyt U. S. Patent No. 1,333,111 of March 9, 1920.

The invention claimed is:

1. In combination a line, means for loading said line for one range of frequencies, loading coils uniformly distributed along said line for loading said line for another range of frequencies, and a condenser connected effectively in shunt to each of said loading coils and having a value sufficient to make said condenser substantially opaque to the frequencies to be loaded by said coils, each such parallel combination of condenser and loading coil being connected in series with said means for loading said line for said one range of frequencies.

2. In combination a line, loading coils distributed along said line for loading said line for one range of frequencies, other loading coils distributed along said line at greater intervals than said first coils for loading said line for a lower range of frequencies, and a condenser connected effectively in shunt to each of said second mentioned coils and having a value sufficient to make said condensers substantially opaque to the frequencies to be loaded by said second coils, each such parallel combination of condenser and loading coil being connected in series with said first mentioned loading coils.

3. In combination a line, means for loading said line for one frequency range, loading coils distributed along said line for loading said line for another frequency range, a condenser connected effectively in shunt to each of said loading coils, said condenser having a value forming with each loading

coil a circuit anti-resonant for a frequency intermediate the two mentioned frequency ranges.

4. In combination a line, means for loading said line for one frequency range, loading coils distributed along said line for loading said line for another frequency range, a condenser in shunt to each of said coils, said condenser having such a value that for one frequency range the combined coil and condenser presents a substantially inductive reactance, and for another range presents a substantially capacitative reactance.

5. In combination a line, loading coils for loading said line for one frequency range, other loading coils for loading said line for another frequency range, a condenser in shunt to each of said other loading coils, said condenser having such a value, that the combined coil and condenser presents a substantially inductive reactance for the frequencies to be loaded by the shunted coils and a substantially capacitative reactance for the frequencies to be loaded by the remaining coils.

6. In combination a line, loading coils distributed along said line for loading said line for telephone frequencies, loading coils distributed along said line at greater intervals for loading said line for low frequency telegraph, and a condenser in shunt to each of said second loading coils, said condenser having such a value that the condenser and the shunted loading coil form a closed circuit anti-resonant at a frequency intermediate the telephone frequency band and the low frequency telegraph band.

7. In combination a line, means for loading said line for one range of frequencies, loading coils uniformly distributed along said line in series with said loading means for loading the line for another range of frequencies, and a condenser connected effectively in shunt to each of said loading coils

and having a value sufficient to make said condenser substantially opaque to the frequencies to be loaded by said coils.

8. In combination a line, loading coils distributed along said line for loading said line for one range of frequencies, other loading coils connected in series with said first mentioned loading coils distributed along said line at greater intervals than said first coils for loading said line for a lower range of frequencies, and a condenser connected effectively in shunt to each of said second mentioned coils and having a value sufficient to make said condensers substantially opaque to the frequencies to be loaded by said second coils.

9. In combination a line, means for loading said line for one frequency range, loading coils connected in series with said loading means distributed along said line for loading said line for another range of frequencies, a condenser connected effectively in shunt to each of said loading coils, said condensers having a value forming with each loading coil a circuit anti-resonant for a frequency intermediate of the two mentioned frequency ranges.

10. In combination a line, loading coils of two kinds in said line for respectively loading said line for two ranges of frequencies, the loading coils of one kind being connected in series in said line with the loading coils of the other kind and being connected so that the currents of the lower frequency range pass through the coils of both kinds, and means for by-passing the currents of the higher range of frequencies around the coils which load the line for the lower frequency range.

In witness whereof, I hereunto subscribe my name this 18th day of October, A. D. 1922.

ROBERT C. MATHES.
